(57) **CLAIM**

We claim the ornamental design for an odor control dispenser, as shown and described.

DESCRIPTION

FIG. 1 is a front perspective view showing our new design of an odor control dispenser;
FIG. 2 is a rear perspective view of the odor control dispenser;
FIG. 3 is a front elevation view of the odor control dispenser;
FIG. 4 is a rear elevation view of the odor control dispenser;
FIG. 5 is a bottom view of the odor control dispenser;
FIG. 6 is a top view of the odor control dispenser; and,
FIG. 7 is a left side elevation view of the odor control dispenser.
